UNITED STATES PATENT OFFICE

CHARLES B. JACOBS, OF BALTIMORE, MARYLAND

SLIP-ON GARMENT

Application filed September 8, 1932. Serial No. 632,098.

The present invention relates to improvements in women's house dresses, and pertains more specifically to that type of women's house dress known as the Hoover type of garment, dress or coat structure.

This particular type of dress, i. e., the Hoover type, has a number of advantages that are more or less well known to the average housewife, such as the convenience with 10 which it may readily be put on or taken off like a coat, due to its coatlike structure or design; the double front feature permitting either side to be lapped over the other side, thus allowing for longer wear or use as to 15 cleanliness of appearance, together with the use of a belt that may be permanently attached to the garment for properly confining the same to the person. These and other advantages are well known as to this type of 20 house dress.

Heretofore the dress manufacturers have more or less confined their attention in a manufacturing sense as to this type of dress, to its usefulness and utility only as to design, in relation to its many advantages to 25 the wearer, and from all indications, have been greatly influenced thereby. In other words, the structural design of this garment as to and in relation to its utility, seems to 30 have been the uppermost thought in the minds of the manufacturer.

The present inventor, having these advantageous features in mind, and having had 35 years of practical experience in the dress manufacturing industry, has gone a step further and invented a Hoover type garment having all the aforementioned features but having in addition, the present invention applied thereto of a new type of Hoover garment structure and design which renders the 40 garment more pleasing to the eye, one that will positively adapt and conform itself to the wearer's figure, and does not present the usual bagginess which tends to give the wearer a clumsy appearance. The present invention of garment structure also tends to give 45 the wearer a snappy and trim figure which is a very desirable feature to the trade, and for 50 those who usually purchase this type of gar-

ment, such as nurses, maids, beauticians, attendants and housewives.

From practical demonstrations, this improved garment, it has been found, will automatically adjust itself to the wearer's figure, due in great measure to its structural design, its fashionable cut and princess flare back.

This is a new garment, being buttonless, and because of its new structural design, as 60 applied to the Hoover garment, is very easily laundered because it spreads flat, particularly in a longitudinal direction. Other like garments, with their transverse seams, which at times are puckered, present great difficulty 65 in ironing.

In the accompanying drawing I have illustrated the various features of my invention in their preferred form as applied to the 70 Hoover type of garment or dress.

In the drawing:

Figure 1 is a front elevation of my improved type of Hoover dress, disclosing the same as it appears when actually worn, the right side being shown held open and away 75 from the wearer's body.

Figure 2 is a rear elevation of the garment and figure as shown in Figure 1.

Figure 3 is another view of the back of the garment disclosing its lines without the belt. 80

Figure 4 is a three quarter or perspective view of the garment disclosing the left side of the same as it appears when extended outwardly.

Figure 5 is a rear elevation of the improved 85 garment disclosing both front portions spread outwardly for purposes of disclosing the relative lines of the garment and its complete structural design.

Figure 6 is a view similar to Figure 1, 90 somewhat in perspective, and on a reduced scale, illustrating my improved garment in closed position on a wearer with the belt tied somewhat to the left side.

Referring to the drawing by reference numerals, each of which represents the same or similar parts throughout the various views, the invention consists of a body portion 1, having the usual collar and lapel structure 2 formed thereon, with short cuffed 100

sleeves 3, together with right and left hand overlapping front portions 4 and 5, respectively, the upper parts 6 and 7 of which are provided with the permanently attached belt members 8 and 9, respectively. Either of these belts may be threaded through their respective garment openings 10 and 11, depending on which front portion, either 4 or 5, the wearer wishes to wear on the outside. 10 As shown in Figures 1, 2 and 6 of the drawing, the belt 9 is threaded through its respective belt opening 11, thence brought around the back of the wearer (see Figure 2) to the front, as shown in Figure 1. The right 15 front portion 4 is then overlapped over the left portion 5 and the two free ends of the belts 8 and 9 tied in a manner similar to that shown in Figure 6. These front portions, 4 and 5, may each be provided with pockets 20 14 and 15, respectively, which, as may be readily seen, allows for the provision of a pocket regardless as to which side of the front structure may be in use.

The body structure 1, as a whole, is made 25 up of a plurality of longitudinal garment sections 16, 17 and 18, together with the front sections 4 and 5. For purposes of obtaining a natural conformation of the garment to the average wearer's figure, these 30 longitudinal sections are flared at their upper shoulder and lower skirt portions. The lines 19, 20, 21 and 22 formed by the seams of these sections all tend, as noted from the various figures in the drawing, to converge 35 toward the waist line 23, thus causing the garment to not only assume a form fitting appearance, but to tend to force the garment to lay against the wearer's conformation of figure.

40 It will be noted that the applicant's garment has fully dispensed with any type of transverse waist seam, as this type of structure tends to cause the garment to pull and pucker at the waist line and positively fixing 45 the waist line of the garment which is very objectionable, whereas the applicant's structure presents a flexible waist line that is not definite and allows the garment to more readily conform itself to the varying waists and 50 hips of the different body types of wearers. The longitudinal sections, 16, 17 and 18, permit the manufacturers to incorporate the very desirable type of princess flare back to this garment.

55 I have thus described specifically and in detail a garment structure of the Hoover type embodying the various features of my invention in their preferred form in order that the nature and operation of the same 60 may be clearly understood, however, the specific terms herein are used descriptively rather than in a limiting sense, the scope of the invention being defined in the claim.

65 What I claim as new and desire to secure by Letters Patent is:

A house dress having a neck portion at the top and a back and side portion formed of continuous vertical sections joined at the edges, the sections having an oppositely reducing taper from the collar portion and the 70 bottom edge respectively, toward the waist, the garment also having a front section on each side, each front section being adapted to overlap the other front section at and below the waistline, each front section below 75 the waistline extending substantially across the entire front of the garment and having an offset at the waist line providing a horizontal edge extending along the waistline, each front section above the offset being narrowed relatively to its lower portion by the offset and having its free edge inclined outwardly from the offset and upwardly toward the neck, said inclined edges being provided with a collar turned over the corresponding 80 front sections, the collar extending continuously from the offset at the waistline at each side upwardly and around the neck and tapering downwardly to a point at both ends of the collar which points meet the inclined 85 edges at the waistline and a belt section secured to each offset, the ends of the belt being adapted to be connected at the front, the garment having an aperture at each side on the waistline through which the belt sections 90 on the opposite sides may be passed, the aperture on the overlapping side of the garment only being utilized by passing the belt section on the side which is covered through said aperture and around the back of the wearer 95 and joining with the other belt section at the front.

Signed by me at New York, New York, this 6th day of September 1932.
